SUCTION MOUNTING

Frederick A. Wayne, Detroit, Mich.

Application June 7, 1937, Serial No. 146,793

2 Claims. (Cl. 248—362)

This invention relates to improvements in suction mountings, and refers to mountings intended for use upon the legs of comparatively heavy articles to be held in position upon highly finished surfaces, as for instance carrier frames to be mounted upon the tops of automobiles. At the present time suction mountings consisting of inverted cups are frequently employed for holding articles to which they are attached upon other articles. These mountings, however, are open to the grave objection that when subjected to sudden loads they are apt to collapse in which case the central portion of the cup suddenly contacts the surface on which it is mounted and is very liable to dent or mar a highly finished surface.

This invention aims, among other things, to provide a suction mounting in which complete collapse cannot occur so that highly polished surfaces cannot be dented or marred if a sudden pressure is exerted upon the mountings even if the latter are utilized upon vehicles where they are also subjected to vibration.

Another object of the invention is to provide a suction mounting consisting of an inverted cup having a central downwardly projecting resilient pad which normally terminates above the underside of the cup so that the bottom of the pad will contact the surface on which the mounting is arranged and prevent complete collapse of the cup when the mounting is subjected to a sudden load.

Another object of the invention is to provide such a suction mounting wherein an air space is maintained at all times within the cup and around the pad to preserve the suction hold of the mounting.

Having thus briefly stated some of the major objects and advantages of the invention, I will now proceed to describe preferred embodiments thereof with the aid of the accompanied drawing in which:

Figure 1 illustrates a sectional view of the suction mounting when not in use, and

Figure 2 is a similar view of the mounting in use.

Figure 3 is a plan view of a carrier to which the mountings are applied to retain it upon the top of an automobile, and

Figure 4 is a side view of Figure 3 partly in section.

Figure 5 is a partial sectional view showing a slight modification of the mounting.

Referring to the drawing, 1 designates the roof of a vehicle on which a carrier 2 is arranged.

The latter consists of a rectangular frame 3 having reinforcing strips 4 secured longitudinally upon the inner faces of its sides intermediately of the length of the latter. 5 denotes diagonal braces across the inside of the frame 3 from the extremities of the strips 4 to the frame ends. The upper edge faces of the strips 4 and braces 5 terminate below the upper edges of the frame 3 so that a box (not shown), or other structure, may be supported upon the said edge faces of the strips 4 and braces 5 with its base beneath the top of the frame 3. Secured to the corners of the latter and projecting downwardly therefrom are legs 6, which, in the present case, are externally threaded at their lower extremities to engage correspondingly threaded openings 7 formed in upwardly projecting bosses 8 integral with the suction mountings 9.

Referring now to the mounting 9. 10 denotes an inverted suction cup which usually terminates at its lower extremity in an annular base 11 of increased width. The cup 10 may also be reinforced by substantially vertical ribs 12 projecting from its inner face intermediately of its height. Extending downwardly from the underside of the cup 10 concentric with the boss 11 is a neck 14 of a pad 15. The main portion of the latter which extends from the bottom of the said neck is of enlarged cross section, normally terminates above the base 11 of the cup 10, and its underside normally lies parallel with the underside of the said cup base.

The mounting 9, including the cup 10, ribs 12 and boss 11, are moulded in one piece of rubber or other resilient composition, and the pad 15 including its neck 14 may either be separated moulded, also of a resilient material such as rubber, and adhesively secured both to the underside of the cup 10 and also to the ribs 12 as indicated at 16, or else the entire mounting 9 and pad 15 may be moulded together in one piece.

Due to the fact that the cup base 11 first contacts the surface to which the mounting is to be applied the cup 10 becomes somewhat distorted, and therefore intermediately of its height the cup is somewhat outwardly flexed before the pad 15 contacts the said surface. Consequently an air space is always maintained within the cup and around the pad to insure the retention of a suction hold. It may also be pointed out that whereas in the construction described the pad 15 joins the ribs 12 for a short distance along the latter the spaces between the ribs afford free air passage at all times from the annular space within the bottom of the cup to the space around the 55

neck 14. In the modified arrangement shown in Figure 5 the pad 15a is of somewhat smaller perimeter so that no contact between the ribs 12a and the said pad 15a is made; thus further insuring an annular air space at all times within the cup. Again due to the resilience of the material of which the cup and pad are made they will readily conform to whatever curvature there may be on the surface to which they are applied as shown clearly in Figure 4.

Thus it will be readily seen that the pads 15, or 15a, effectually protect the surface upon which the mounting rests from any sudden blow that it might receive due to the collapse of the cup 15 if that said pad were omitted.

While in the foregoing the preferred embodiments of the invention have been described and shown, it is understood that the construction is subject to such further alterations and modifications as fall within the scope of the appended 20 claims.

What I claim is:

1. A suction mounting comprising a resilient inverted cup the lower annular face of which is 25 adapted to rest upon a surface and maintain a suction grip thereon, a stepped resilient pad dependingly mounted within the cup and its base being adapted to bear upon said surface, the upper portion of the pad being of smaller diameter than the lower portion and both pad portions being 30 annularly spaced from the interior of the cup thereby forming upper and lower air spaces around them, the upper extremity of the lower portion of the pad bearing against said ribs between which passages are formed normally connecting the upper and lower air spaces, said cup and the lower pad portion being adapted to be pressed together around their entire circumferences by sudden downward pressure exerted upon the mounting thereby closing the underside of the upper air space, and means on the upper side of the cup to receive an article to be supported.

around the upper pad portion and a lower air space around the lower pad portion, said cup and the lower portion of the pad being adapted to be pressed together around the entire pad perimeter by sudden downward pressure exerted upon the 5 mounting whereby the underside of the upper air space is closed and complete collapse of the cup is prevented, and means on the upper side of the cup to receive an article to be supported.

2. A suction mounting comprising a resilient 10 inverted cup the lower annular face of which is adapted to rest upon a surface and maintain a suction hold thereon, a plurality of inwardly disposed radial ribs formed inwardly of the cup intermediately of its height, a circular resilient 15 pad stepped intermediately of its height dependingly mounted within the cup and having a base adapted to bear upon said surface, the upper portion of the pad being of smaller diameter than the lower portion and both pad portions being 20 annularly spaced from the interior of the cup thereby forming upper and lower air spaces around them, the upper extremity of the lower portion of the pad bearing against said ribs between which passages are formed normally connecting the upper and lower air spaces, said cup and the lower pad portion being adapted to be 25 pressed together around their entire circumferences by sudden downward pressure exerted upon the mounting thereby closing the underside of the upper air space, and means on the upper side of the cup to receive an article to be supported.
